UNITED STATES PATENT OFFICE.

WILHELM SCHÜTZ, OF DUSSELDORF, GERMANY.

MASONRY COAT HOLDER FOR MORTAR AND THE LIKE.

Application filed October 15, 1924. Serial No. 743,665.

To all whom it may concern:

Be it known that I, WILHELM SCHÜTZ, a citizen of Germany, and residing at 19 Schlossstrasse, in the city of Dusseldorf, 5 Germany, have invented certain new and useful Improvements in Masonry Coat Holders for Mortar and the like, of which the following is a specification.

This invention has reference to sheet 10 metal carriers for the exterior coatings of masonry, generally designated by various names as rendering, laying or pricking-up coat, slipped coat, finishing coat, screeding, rough casting, whitewash, and the like, 15 and it is intended to overcome the drawbacks and inconveniences heretofore encountered with sheet metal carriers of the kind referred to, and to greatly increase the adaptability and durability of such carriers. 20 According to the previous art either perforated or unperforated sheets were utilized for the purpose in question. With a view of increasing the adhesion of the coat to the sheet metal the unperforated sheets have 25 heretofore been bent either entirely or in part, so as to constitute dove-tail portions, or similar members have been connected to the sheets by riveting or such members were provided by cutting out and suitably bending 30 parts of the sheet. Now all such detached elements are stretched and distorted upon being subjected to tensional stresses and to strains, and are liable to be sheared off, and on account of the reduction of the operative 35 surface produced by the formation of these members they entail a great consumption of constructional material. Furthermore, plain metal sheets are considerably weakened by the perforations and are likely 40 to be leaky and present leaks, even in case the perforations are closed by rivets, and this is particularly the case with thin sheets which can only be cold-riveted, and whenever 45 they are submitted to variations of shape.

My invention provides for a novel carrier in which these difficulties are avoided by doing away with perforations and cuts, and leaving the sheet entirely uninjured, so as to 50 cause it to preserve its full supporting capacity and tightness irrespective of all alterations of shapes. The novel carrier moreover, is superior to the sheet metal carriers referred to as regards economy of manufac-

ture and ease and convenience of employment.

Upon the accompanying drawing I have shown by way of example and in a conventional manner a sheet metal carrier embodying the principles of my invention 60 in Figure 1 in cross section on the line 1—1 of Figure 2 with a diagrammatic indication of the masonry. Figure 2 is an elevation of the carrier, and Figure 3 is a modification in which the carrier takes the shape of a 65 pipe or of a hollow pillar.

In the drawings:—*a* is the sheet metal plate *b* are the holders of any suitable configuration, for instance, dish shaped, though my invention is by no means limited 70 to this particular form of holders which may comprise smaller strips or pieces of sheet metal *b*, *d* or the like which are secured to the main sheet *a* by welding or the like without perforating or otherwise weakening the main sheet, and which, with the exception of the point of attachment *c* only are protruding from said main sheet. The said small sheet metal pieces *b*, *d* may be 75 preferably secured to the main sheet of any suitable shape and configuration by an electric spot welding process or the like by means of which they are attached at one point only. If desired, such holders may be secured on both sides of the main sheet. 80 In the latter case the holders for the coating are most conveniently arranged opposite each other, and are connected to the main sheet by one single welding point *c*.

It is obvious that by proceeding in this 90 manner the main sheet is not injured nor weakened nor is it liable to present leaks. It should be understood, of course, that the invention is by no means restricted to the particular shapes and configurations and steps of proceeding herein shown and described, but the invention is broad enough to admit of modifications and changes within the scope of the claims hereunto appended.

I claim:—

1. A sheet metal carrier for masonry and the like, comprising a main sheet metal body, and a plurality of spaced unitarily formed concavo-convex sheet metal members disposed upon a surface of said main sheet metal body with their convex faces lying in direct abutting contact therewith the abutting portions of the main sheet

100

105

metal body and concavo-convex sheet metal members being imperforate and integrally joined.

2. A sheet metal carrier for masonry and the like, comprising a main sheet metal body, and a plurality of parallel, spaced unitarily formed linear strips of sheet metal disposed upon a surface of said main sheet metal body, each strip being transversely of concavo-convex form and having its convex face lying in direct abutting contact with said surface of the main sheet metal

body, the abutting portions of the main sheet metal body and the sheet metal strips being imperforate and integrally joined. 15

3. A sheet metal carrier for masonry and the like, comprising a sheet metal body of cylindrical form, and unitarily formed transversely dished linear sheet metal strips having their convex faces lying in direct 20 surface contact with a surface of said cylindrical body and joined thereto.

WILHELM SCHÜTZ.
